DESIGN FOR A DIRECTION SIGNAL SWITCH

Henry G. Dibelka, Chicago, Ill., assignor to Auto Radiator Manufacturing Co., Chicago, Ill., a corporation of Illinois

Application January 9, 1939, Serial No. 82,257

Term of patent 7 years

To all whom it may concern:

Be it known that I, Henry G. Dibelka, a citizen of the United States and a resident of Chicago, Cook county, Illinois, have invented a new, original, and ornamental design for a Direction Signal Switch, of which the following is a specification, reference being had to the accompanying drawing forming part thereof, in which

Fig. 1 is a top plan view;

Fig. 2 is a side elevation view from the right of Fig. 1; and,

Fig. 3 is a front elevation of a direction signal switch, showing my new design.

I claim:

The ornamental design for a direction signal switch, substantially as shown.

HENRY G. DIBELKA.
